CLAIM

The ornamental design for a maternity brassiere closure with indicator, as shown and described.

DESCRIPTION

FIG. 1 is a front elevation view of a maternity brassiere closure with indicator showing our new design;

FIG. 2 is a side elevation view of the maternity brassiere closure with indicator, the opposite side view being a mirror image; and,

FIG. 3 is a rear elevation view of the maternity brassiere closure with indicator.

Our maternity brassiere closure with indicator is intended for use in fastening the cups of a maternity brassiere.
